(57) **CLAIM**

The ornamental design for a container with lid, as shown and described.

DESCRIPTION

FIG. 1 is an exploded top perspective view of a container with lid, illustrating the lid adjacent the top of the container, showing my new design;

FIG. 2 is a top perspective view of the container with lid, illustrating the lid seated on the top of the container;

FIG. 3 is a sectional view taken along 3-3 in FIG. 2;

FIG. 4 is an exploded bottom perspective view of the container with lid, illustrating the lid adjacent the bottom of the container;

FIG. 5 is a bottom perspective view of the container with lid, illustrating the lid seated on the bottom of the container;

FIG. 6 is a sectional view taken along 6-6 in FIG. 5;

FIG. 7 is a front elevational view of the container with lid shown in FIG. 5;

FIG. 8 is a rear elevational view thereof;

FIG. 9 is a left side elevational view thereof;

FIG. 10 is a right side elevational view thereof;

FIG. 11 is a top plan view thereof; and,

FIG. 12 is a bottom plan view thereof.

The dot-dot-dash lines depict portions of the container with lid that form no part of the claimed design.

1 Claim, 7 Drawing Sheets
